UNITED STATES PATENT OFFICE.

EDWIN ROSS, OF NEW YORK, N. Y., ASSIGNOR TO WOODWORTH INCORPORATED, OF NEW YORK, N. Y., A CORPORATION OF NEW YORK.

DESIGN FOR A VANITY BOX.

Application filed January 19, 1923. Serial No. 4,937. Term of patent 7 years.

To all whom it may concern:

Be it known that I, EDWIN Ross, a citizen of the United States, residing at New York, county of New York, State of New York, have invented a new, original, and ornamental Design for a Vanity Box, of which the following is a specification.

This invention relates to a new, original and ornamental design for a small box for containing toilet accessories and commonly known as a vanity box, and the invention consists in the peculiar surface ornamentation on the cover of the box, substantially as shown in the accompanying drawing forming a part of this specification, in which the

I claim.

The ornamental design for a vanity box as shown and described.

EDWIN ROSS.
